HERBERT V. FOSTER, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS

WEIGHT FOR WEFT-REPLENISHING-LOOM THREAD HOLDERS

Application filed December 20, 1928. Serial No. 327,438.

This invention relates to an improved form of weight to be used for the weft threads of weft replenishing looms and it is the general object of the invention to provide a weight 5 easily applied to the weft threads.

In weft replenishing looms particularly of the multicolor type there are a number of weft threads extending from the reserve bobbins which should be kept taut to insure best 10 operation for the loom. Certain forms of thread holders make use of weights which are attached to the weft ends and it is an important object of my present invention to provide a weighted element for a magazine, 15 the element being readily attachable to a weft end by a single operation on the part of the user. It is highly desirable that the weaver be able to apply the weights quickly and also securely, the weight preferably being manipulated by one hand and the thread 20 with the other and it is a further object of my invention to provide a weight which can be thus operated.

With these and other objects in view which 25 will appear as the description proceeds, my invention resides in the combination and arrangement of parts hereinafter described and set forth in the claim.

In the accompanying drawings wherein 30 a convenient embodiment of my invention is set forth,

Fig. 1 is an end elevation of a weft replenishing mechanism showing weft ends provided with my improved weight,

Fig. 2 is a vertical section through a portion 35 of the thread holder to illustrate the manner in which the thread holder may be held in non-clamping position to permit my improved weights to tension the weft threads,

Fig. 3 is an enlarged vertical section 40 through one of my weights, and

Fig. 4 is a diagrammatic view illustrating the manner in which a weft thread may be applied to the weight.

As shown in Fig. 1 there is a magazine M 45 from which extend a plurality of weft threads W from the reserve bobbins not shown. These threads may extend between the coils of a spring 10 substantially of the 50 form shown in co-pending application Ser.

No. 326,057 filed by Tinsley. Said spring may be anchored with respect to the magazine by means of a stationary collar 11 mounted on a fixed rod 12. A manually operated spring controller 13 is slidably mounted on 55 the rod 12 and is operatively connected to the left hand end of the spring as viewed in Fig. 1. A latch 14 may be used to engage a portion of the controller 13 to hold the same in spring expanding position as shown in 60 Fig. 2.

The matter thus far described forms no 65 part of my present invention and is set forth to show the conditions under which my improved form of weight may be used. In the operation of the magazine the bobbins descend, thus causing slackness on the part of the weft threads W. The controller 13 will be periodically moved to the left to separate the coils of the spring 10, thus freeing the 70 weft ends from the clamping action of the coils. When this happens it is desirable to have some agency operative to tension the 75 weft threads to take up their slack and it is to accomplish this result that I have provided an improved form of weight.

Referring to Fig. 3 I have provided a long slender rod 20 having a head 21 formed on the lower end thereof. A tube or sleeve 22 surrounds the rod and is freely slidable on the latter, being urged upwardly by a spring 23 interposed between the head 21 and the lower end of the sleeve 22. Upward movement of the sleeve with respect to the rod is limited by means of a stop 24 which may 80 be secured to the rod in any approved manner as by means of a pin 25. Any other form of stop may be employed, but it is desirable that the stop present a lower surface 26 which will cooperate with upper surface 85 27 of the sleeve 22 to pinch a weft end.

The manner of using my invention is set 90 forth in Fig. 4 where it will be seen that the rounded head 21 may be located in the palm of one hand while the fingers move the sleeve 95 down against the action of spring 23, thus separating the surfaces 26 and 27. The weft end W may then be passed under the stop 24 and the sleeve released, whereupon the 100 spring 23 will move the surface 27 against

the weft to clamp the latter against the surface 26. The weft end may then be passed down over the spring 10 to be located between adjacent coils when the latter are spaced.

From the foregoing it will be seen that I have provided a very simple form of weight which can be readily attached to a weft end, said weft comprising a pair of thread clamping surfaces which are forced together by a resilient device, the whole being so constructed that it can be operated by one hand leaving the other hand free for the manipulation of the weft thread. It will also be seen that the lower portion of the head 21 is rounded so that should the heads be of different elevations in the magazine the higher weights will be able to move downwardly without being held up by adjacent weights.

Having thus described my invention it will be seen that changes and modifications may be made therein by those skilled in the art without departing from the spirit and scope of the invention and I do not wish to be limited to the details herein disclosed, but what I claim is:

A weighted thread tensioning element for a weft replenishing loom having weft ends, said element comprising a rod, a stop located at the upper end thereof, a sleeve slidably mounted on the rod, a head formed on the lower end of the rod, and a compression spring interposed between the head on the rod and the lower end of the sleeve and acting to move the sleeve against the stop to clamp a weft end, said sleeve being yieldable to move away from the stop to release a weft end, the lower portion of said head being rounded to facilitate movement of the same with respect to adjoining weighted elements.

In testimony whereof I have hereunto affixed my signature.

HERBERT V. FOSTER.
